J. Edward Thebaud.

UNITED STATES PATENT OFFICE.

KIRKE R. WILSON, OF BUFFALO, NEW YORK.

REAMING MACHINE.

1,413,550.

Specification of Letters Patent. Patented Apr. 18, 1922.

Application filed January 9, 1920. Serial No. 350,426.

To all whom it may concern:

Be it known that I, KIRKE R. WILSON, a citizen of the United States, residing at Buffalo, in the county of Erie and State of New York, have invented certain new and useful Improvements in Reaming Machines; and I do hereby declare the following to be a full, clear, and exact description of the same, such as will enable others skilled in the art to which it appertains to make and use the same, reference being had to the accompanying drawings, and to figures of reference marked thereon, which form part of this specification.

15 Like figures of reference refer to like parts.

This invention relates to reaming machines.

One of the objects of this invention is to 20 provide a device adapted to hold the article to be reamed in a fixed position, and at the same time guide the reaming tool in a manner to cause the reamer to cut a cylindrical bearing surface of the desired size, practically co-axial with the piece that is reamed.

Another object is to provide a reaming machine of one integral piece adapted to fix in position any one of a variety of pieces concentric and co-axial to a part of the reaming machine serving as a guide to the shank of the reamer.

Another object of this device is to provide a reaming machine especially adapted to concentrically ream the bearings of the 35 various gear members of the transmission of an automobile.

With these and other objects my invention resides in certain construction, one embodiment of which is illustrated in the drawings, is hereinafter described, its application 40 is explained and what I claim is set forth.

In the drawings,

Figure 1 is a front elevation of a reaming machine embodying my invention.

45 Figure 2 is a top plan of the device shown in Figure 1.

Figure 3 is a vertical section through the axis of the machine taken on the line X—X of Figure 1.

50 Figure 4 is a plan view of the yoke used in conjunction with the main piece of the machine, for holding an article in place while spanning the face of the machine.

Figure 5 is a section taken on the line

55 Y—Y of Figure 4.

Figure 6 is a front elevation of the ream-

ing device showing the reverse transmission drum of a Ford automobile fixed in position thereon, for reaming a new bushing, which had been previously forced into 60 the center of the drum.

Figure 7 is a vertical and axial section taken on the line A—A of Figure 6, and illustrates the position of the reamer partly entered in the bushing. 65

Figure 8 is a front elevation of the reaming device showing the slow speed drum with gear of a Ford automobile transmission, fixed in position thereon.

Figure 9 is a vertical axial section taken 70 on the line B—B of Figure 8, and shows a smaller reamer than that shown in Figure 7, but having the same size shank.

Figure 10 is a front elevation of the reaming machine showing concentrically fixed 75 thereon, the transmission brake drum of a Ford automobile.

Figure 11 is a vertical axial section taken on the line C—C of Figure 10, showing the brake drum to have a bushing in each end 80 thereof, and illustrates the special reamer designed for this particular purpose, but having its main shank the same size as the reamers shown in Figures 7 and 9.

Figure 12 is a front elevation showing the 85 triple gear of a Ford automobile transmission fixed in position thereon, in connection with the yoke shown in Figure 4.

Figure 13 is a vertical axial section taken 90 on the line D—D of Figure 12, illustrating the position of the gear thereon, together with the special reamer required for this purpose, and having a shank of the same diameter as the shanks of the reamers shown in Figures 7, 9 and 11. 95

Figure 14 is a perspective view of the bar wrench used to turn any of the reamers shown in the figures.

In the figures, the reaming machine is shown to be made practically of a single 100 casting with a few attachments, wherein the base 1, has projecting above it, a disk portion 2, having a flange 3, which is machine faced on the surface 4, as well as upon the interior cylindrical surface 5, and also upon the flat zones 6 and 7, of the inside of the disk portion 2. The upper part of the flange 3^a is separated from the disk portion 2, by a saw cut 8. The portion 3^a is divided at the top, where each part terminates in an 105 upstanding ear 9. These ears are adjustably forced together by means of the bolt 10, and

the wrench 11, in threaded engagement with the bolt 10 and in contact with one of the ears 9. The flange 3 has perforated ears 12 and 13 for the reception of clamping hooks 14 and 15, each having a thumb screw 16. Concentrically positioned with respect to the cylindrical surface 5, is the cylindrical pocket 17, having a machined cylindrical surface 17^a, which is truly concentric and co-axial with the cylindrical surface 5. Extending to the rear of the pocket 17, is the long cylindrical hole 18, the surface of which is machined co-axial with the surface 5. A web 19 extends up from the base 1 and is incorporated with the walls of the pocket 17 and of the hole at 18.

In Figure 4 is shown a yoke 20, having a central hole at 21, flanged at 22. The body of the yoke 20 has a flange 23 extending from the surface thereof in the opposite direction to that of the flange 22. The length of this yoke 20 is such as to be engaged between and by the hooks 14 and 15, when a piece, engaging the surface 17^a, and having its largest diameter smaller than that of the surface 5, is positioned upon the reaming machine.

The Figures 6 to 13 inclusive show the device illustrated in Figures 1 to 5 inclusive, having various parts of a Ford transmission concentrically and co-axially held thereon for the reaming of the bearings. In Figures 6 and 7 is shown the reverse transmission drum 24 of a Ford automobile, having a bushing 25 to be reamed co-axial with the peripheral cylindrical surface 26, which surface co-fits with the cylindrical surface 5, of the reaming machine, having a flange 27 fully in contact with the flat surface 4. The ears 9 are drawn together by turning the wrench 11, so as to fix the drum firmly and co-axially within the machine. Previous to putting the drum 24 in place, as just described, the reamer 28 is positioned, having its shank 29 in sliding and turning engagement with the cylindrical surface 18 of the machine. The shank 29 terminates in engagement with the bar wrench 30 for turning the reamer. The hooks 14 and 15 are used in positioning and holding the drum 24 in place against the surface 4.

Referring now to Figures 8 and 9, which illustrate the slow speed drum gear of a Ford transmission in place on the reaming machine, wherein the slow speed drum 31 replaces the reverse drum shown in Figures 6 and 7, and wherein the bushing 32 is to be reamed, the reamer 33, required for the slow speed bushing is smaller than that required for the reverse drum bushing, but has a shank 34 of the same diameter as the shank 29 fitting the same hole.

Referring now to Figures 10 and 11, which concern the reaming of the transmission brake drum 35 of a Ford automobile, the

periphery of this drum is the same as that of the reverse and slow speed drums, and consequently adapted to fit within the surface 5, and to be clamped therein by means of the clamp at 9. The drum 35 has a cylindrical projection 36, in the outer end of which, is the flangeless bushing 37, and at the inner end of which is the flanged bushing 38. Each of these bushings has the same internal diameter and is forced into the place shown in section in Figure 11. The reamer in this case is somewhat differently constructed than the reamers shown in Figures 7 and 9, in having in addition to the shank 39 which is the same diameter as that of the shanks 29 and 34, a shank portion 40, of a diameter equal to the finished diameter of bushing 38, as left by the reaming portion 41, and serves as a guide to the reamer, when the same is advanced into the bushing 37, to preserve the co-axial arrangement of the finished surfaces of the bushings with one another and with the drum.

Referring to Figures 12 and 13, there is shown positioned upon the reaming machine 90 a triple gear 42, wherein the smaller gear 43, of the three gears, has a sliding fit concentrically and co-axially within the cylindrical surface 17^a, of the pocket 17. The central or larger gear 44, is in contact with the zone surface 7 of the machine. In order to hold this gear in this position upon the machine, the yoke 20 is made to engage the triple gear, having its flange 22 in engagement with an annular recess in the gear 45. The yoke 20 is clamped into place at its ends by the hooks 14 and 15. The reamer in this case has a shank 46, which has the same diameter as the shanks 29, 34 and 39, shown in the other figures, and the reaming portion 47 is of the desired size to ream the bushing 48 of the gear.

The operation of this device has been somewhat indicated in connection with the description of the figures, wherein the shanks of various sized reamers are all the same diameter for a proper sliding fit with the bore of the hole 18, the walls of which, act as a guide to the reamers in maintaining the same, concentric and co-axial to the piece 110 to be reamed, when held concentrically in position upon the machine.

Modifications of the one embodiment of this device herein shown and described, may be made without departing from the spirit 120 and scope of my invention, I therefore, do not wish to be confined to the one embodiment, hence I claim.

1. A reaming machine comprising in combination means for guiding a reamer, a disk 125 concentric and co-axial with said guiding means, an annular flange around said disk, whereby the article to be reamed is supported, means for clamping said flange against said article to hold it in fixed rela- 130

tion to said guiding means, and means carried by said flange to assist said clamping means.

2. In a reaming machine adapted to guide a reamer thereon and to concentrically and co-axially hold any one of a variety of journaled revoluble articles thereon, a composite frame integrally made, said frame having a disk portion, a base supported on said disk portion, an integral flange on said disk portion, the upper part of said flange being cut free from said disk portion and being bifurcated at its top, means connecting said bifurcated portions adjustably to clamp a piece positioned within said flange, and a hollow guiding portion having its bore concentric and co-axial with said flange and adapted to have a sliding fit with the shanks of a variety of reaming tools, operated therein upon any one of said articles.

3. In a reaming machine adapted to guide a reamer thereon and to concentrically and co-axially hold any one of a variety of journaled revoluble articles thereon, a composite frame integrally made, said frame having a disk portion, a base supported on said disk portion, an integral flange on said disk portion, the upper part of said flange being cut free from said disk portion and being bifurcated at its top, means connecting said bifurcated portions adjustably to clamp a piece positioned within said flange, a yoke piece adapted to span the face of said disk flange, attaching means for releasably fixing said yoke piece to said machine to hold an article against said machine to be reamed, and a hollow guiding portion having its bore con-

centric and coaxial with said flange and adapted to have a sliding fit with the shanks of a variety of reaming tools, operated 40 therein upon any one of said articles.

4. In a reaming machine adapted to guide a reamer thereon and to concentrically and co-axially hold any one of a variety of bushed articles to be reamed thereon, a composite frame integrally made, said frame having a disk portion, a base supporting said disk portion, an integral flange to said disk portion, the upper part of said flange being cut free from said disk and being 50 bifurcated at its top, means connecting said bifurcated portions adjustably to clamp a piece positioned within said flange, a central hollow portion to said frame having its inner surface cylindrically and co-axially arranged with reference to the inner surface of said flange, and a hollow guiding portion having its bore concentric and co-axial with said flange and adapted to have a sliding fit with the shanks of a variety of reamers 60 operated therein upon any one of the bushings of said articles.

5. A reaming machine comprising in combination means for guiding a reamer, a disk concentric and coaxial with said guiding means, a bifurcated annular flange around said disk whereby the article to be reamed is supported, means for contracting said flange to position the article in relation to the guiding means and other means carried 70 by said flange for clamping said article against said disk.

KIRKE R. WILSON.
